CLAIM

The ornamental design for a window covering as shown and
described.

DESCRIPTION

FIG. 1 is a front perspective view of the window covering
in a retracted position.

FIG. 2 is a front view of the window covering in the
retracted position;

FIG. 3 is a rear view of the window covering in the retracted
position;

FIG. 4 is a right side view of the window covering in the
retracted position;

FIG. 5 is a left side view of the window covering in the
retracted position;

FIG. 6 is a top view of the window covering;

FIG. 7 is a bottom view of the window covering;

FIG. 8 is a front perspective view of the window covering
in a partially extended position;

FIG. 9 is a front perspective view of the window covering
in a fully extended position; and,

FIG. 10 is a front perspective view of the window covering
in a fully extended position with its shade fabric in an
alternate position.

The contrasting dotted and wave shading shown on the
fabric element is intended to convey two contrasting levels
of translucency.

The break lines shown in the figures symbolize breaks in the
length of the article in which the claimed design is embodied.
The appearance of any portion of the article between the
break lines forms no part of the claimed design.
